GOLF INSTRUCTION DEVICE

Joseph W. Norwood, Los Angeles, Calif.

Application July 3, 1939, Serial No. 282,683

4 Claims. (Cl. 273—35)

This invention relates to golf instruction devices and more particularly to a device adapted to be secured to one wrist of a golf player to facilitate learning the proper strokes in the game of golf. Generally speaking, the invention comprises a seat or guide means for the golf club shaft, said means having a means for positively securing it to one arm of the player and additional means adapted to be gripped, in conjunction with the shaft, by the other hand. Such 10 guide means forms a bridge between the two arms of the player and in addition to stabilizing the proper grip, secures the desired angular disposition of the club to the wrists and hands, particularly at the moment of impact of the club head upon the ball, the arms being fully extended.

In teaching the game of golf to the novice, or in correcting errors which have occurred in the play of more experienced players, it is necessary to instill in the player a knowledge or feeling of the proper relative position of the club shaft, hands and wrists throughout the various strokes. Golf teachers have variously expressed the ends to be attained in such expressions as "keep the left arm straight" and "don't break the left wrist," etc. All of these rules are merely instructions to aid the player to secure the proper relative club, hand and wrist positions. It has been discovered that in a proper stroke with any individual club the angle formed by the club shaft and either of the forearms of the player should not vary materially throughout the swing. While this proper angle may be orally expressed to the pupil, it is a great advantage to provide means to retain this position throughout practice swings so that the pupil has this position unerringly demonstrated to him, enabling him to acquire a feeling or memory for the proper swing.

It is accordingly one object of this invention to provide a golf instruction device which maintains the proper relative position of the club, hands and wrists, for practice strokes.

It is a further object of this invention to provide such a golf instruction device in which a club positioning member is adjustably mounted to accommodate the proper position for the various different clubs.

It is a further object of this invention to provide such a golf instruction device which is simple and economical in construction and light in weight.

Further objects and advantages will appear hereinafter.

In the accompanying drawing:

Figure 1 is an elevation showing the device secured to the arms of a player and indicating a club properly held therein.

Figure 2 is a fragmentary elevation of the club positioning element, the thumb of the player being held back to show the proper positions of the fingers.

Figure 3 is a front elevation showing the club positioning element in detail.

Figure 4 is a plan view of Fig. 3.

Figure 5 is a perspective view of the entire golf instruction device.

Referring more particularly to the drawing, 10 indicates an arm or wrist band, preferably made of leather. The element 10 is provided with a slot 11 through which the narrowed end 12 of the band 10 may be drawn to fasten the band 10 to the arm of the player. A series of snap catches 13 are provided on the narrowed end 12, on the rear thereof as shown in Figure 5, to adjustably fasten the band in conjunction with snap button 14.

The widened portion 15 of band 10 is preferably formed of two pieces of leather 16 and 17. The outer piece 17 has a slot 18 therein for the insertion of the positioning or guide element.

The positioning or guide element includes a curved portion 19 adapted to be inserted into the slot 18 and to lie secured in a pocket formed by the leather pieces 16 and 17. Like the widened portion 15, the curved element 19 should have an approximately frusto-conical taper in order to fit securely to the wrist of the player.

The positioning element is bent to form a member 20 to which is preferably pivotally fastened, as by pivot 21, the club retaining member 22. It will be understood that the pivot 21 provides a frictional contact between member 20 and the flange 23 of retaining member 22. The retaining member 22 will thus be held in the desired position by this frictional contact, but may be pivotally adjusted by the application of a slight turning force. Flange 23 may be provided with beads 24 to limit the arc of pivoting of member 22 to the small arc through which the device may vary in accommodating different clubs. If desired, the members 20, 22, 23 and 25, may be formed of one piece.

Between the flange 23 and retaining member 22 there is provided a spacing member 25. This member 25 is adapted to afford sufficient room for proper gripping of the club and the device by the fingers as clearly illustrated in Figure 2. The retaining member 22 may taper from top to bottom so as to fit the ordinary taper of the usual

golf club as clearly shown in Figures 3 and 5.

The operation of the device is as follows:

With the club retaining member 22 having its portion 19 inserted in the slot 18, the band 10 is secured to the right arm of the ordinary right-handed player and fastened by one of the snaps 13 and button 14. It will be understood that by an obvious reversal of parts the device may be built for a left-handed player. The club is then inserted in retaining member 22 with the fingers of the left hand gripping the club and spacer as shown in Figure 2. The thumb of the left hand will hold the club in the retainer by the usual golf grip as shown in broken lines in Figure 1. For longer clubs, the retainer 22 is pivoted at pivot 21 so as to extend the club head slightly (Figure 1) as will be readily understood.

With the club thus held, the golfer makes his swing. It will be understood that the retainer 22 holds the club shaft in proper position to maintain the correct angle with the right arm, e. g. as indicated in Figure 1. Equally, as the left hand grips the club and the device, the proper positioning of the left arm and hand with respect to the club is maintained. The golfer needs only to fully extend his arms as the club head comes through to contact the ball to be certain that the stroke is correctly made.

In practice it has been discovered that the device is particularly useful in maintaining the exact angular disposition of the club shaft with respect to the arms and wrists at the moment when the arms are fully extended and the club head meets the ball. At this point the device also prevents bending or flexing of the forward wrist, a common error in golf. (The left wrist with a player swinging from a right-hand position, the right wrist for a left-handed player.) It has also been discovered that should the device loosen sufficiently through use to permit the improper bending or flexing of either wrist from the desired position at the moment of impact, an unusual tension is created by the bridge formed by the device, enabling the player to recognize and correct the fault.

I have found the device particularly adapted

for use in putting or in the shorter approach shots but its use is not limited thereto.

While the device may be used by the player at any time as an aid to playing the game, its chief use, due to the rules of golf competition preventing the use of mechanical aids in play, is directed to golf instruction and practice. The pupil, by using the invention, has the correct feel of the club unerringly demonstrated to him and soon acquires a memory of this feeling and teaching the game is greatly facilitated.

It will be understood that while I prefer to form the band 10 of leather and the elements 19 to 25, inclusive, of suitable metal, other durable materials may be used, keeping in mind the desired lightness of the device.

While the particular forms of the invention herein described are well adapted to carry out the objects of the invention, it is to be understood that various modifications and changes may be made without departing from the principles of the invention, and the invention includes all such modifications and changes as come within the scope of the appended claims.

I claim:

1. A golf instruction device comprising an arm band, club retaining means secured to said arm band, said club retaining means including a tapered club retaining member and a finger gripping spacer.

2. A golf instruction device comprising an arm band, club retaining means pivotally secured to said arm band, said club retaining means including a tapered club retaining member and a finger gripping spacer.

3. A golf instruction device comprising an arm band, a curved metallic element secured thereto, a spacer secured to said curved metallic element and a tapered club retaining member secured to said spacer.

4. A golf instruction device comprising an arm band, a curved metallic element secured thereto, a spacer pivotally secured to said curved metallic element and a tapered club retaining member secured to said spacer.

JOSEPH W. NORWOOD.
